AUTOMATIC LEVEL CONTROL

John R. Boykin, Baltimore, Md., assignor to Westinghouse Electric & Manufacturing Company, East Pittsburgh, Pa., a corporation of Pennsylvania

Application May 2, 1942, Serial No. 441,567

5 Claims. (Cl. 178—44)

This invention relates to control circuits, and more particularly, to circuits for preventing excessive voltage magnitudes in an electrical transmission system.

With the trend to high level modulation and higher power transmitters, there is an ever increasing need for a circuit arrangement to prevent high potential surges appearing on the program line of a radio transmitter which would overload the modulation circuit.

An object of this invention is to eliminate the deleterious effect of voltage amplitudes in a transmission circuit exceeding a certain predetermined level and to this end, means are provided for controlling the effective impedance of variable impedance elements shunting said circuit inversely in accordance with the increase of voltage amplitudes.

Another object of this invention is to prevent voltage surges appearing due to unbalance in a balanced transmission circuit which would seriously affect the transmission network. To this end means are provided to control the effective impedance of variable impedance elements in accordance with voltage magnitudes derived from currents produced due to unbalance in the transmission circuit.

A particular feature of the invention is that the variable impedance elements utilized in the transmission circuit comprise vacuum tubes which derive operating potentials from the signal voltage in the transmission circuit and control potentials from the currents produced by unbalance in the transmission line feeding the circuit.

A particular advantage of the control system in accordance with this invention is that the vacuum tubes as impedance elements have infinite impedance at normal operating potentials, whereas upon conditions of unbalance the impedance thereof decreases sharply as the unbalance exceeds a predetermined magnitude.

Other features and advantages will be apparent from the following description of the invention, pointed out in particularity by the appended claims, and taken in connection with the accompanying drawing, in which:

Figure 1 is a schematic circuit arrangement of a balanced transmission system and a control circuit therefor; and

Figs. 2 and 3 show the signal voltage fluctuations in the transmission system with a sudden peak surge and the operation of the control circuit in eliminating the excessive voltage amplitude of the surge.

In radio transmission systems, particularly in broadcasting, the modulation voltage is fed to the system through a balanced program line which feeds the modulation frequency amplifiers. The circuit from the line to the output of the amplifier is generally a balanced network using push-pull amplifying stages. Static disturbances or disturbances from any other source are likely to unbalance the program line, producing excessive voltage surges of short duration. These surges are transmitted in the amplifying system creating voltage peaks which may seriously affect the transmission circuit. Surge voltages may reach such magnitudes that component elements of the transmission system often burn out resulting in interruptions. The transmitted signal is also likely to be marred by the static surges. In radio receivers the loud interference due to static is often created at the transmitter and is picked up from the signal transmission. In other words, the static impulses are part of the broadcast transmission. Devices heretofore used are effective only within a certain voltage range, for example, spark gaps or glow tubes. In certain transmission circuits, the normal operating signal potentials are of sufficiently high value to initiate discharge in glow-discharge type protective devices. In the circuit in accordance with this invention, vacuum tubes are utilized as protective devices in such manner that the anode-cathode impedance of the tubes forms a short circuiting path across the transmission circuit for voltages appearing in excess to the normal signal potentials in the system. The control elements of the vacuum tubes have an initial bias whereby conductance is prevented at the desired value of signal potentials and is effected only when this value is exceeded, and the bias is neutralized by an unbalanced voltage on the transmission line.

Referring to the drawing, in Figure 1 a portion of a program transmission circuit is shown including a balanced input line connected to terminals 1 and 2 feeding into the primary winding 3 of an input transformer 4. The balanced center tap 5 of the winding 3 connects to ground through the primary winding 6 of the transformer 7. Signal potentials appearing across the terminals 1 and 2 are of opposite phase and balance out so that no current will flow through the primary winding 6. The secondary winding 8 of the transformer 4 connects in the conventional arrangement of a push-pull input circuit to the grids 9 and 10 of vacuum tubes 11 and 12, respectively. The input circuit returns to the

cathodes 13 and 14 of the tubes 11 and 12 through a source of bias potential shown here by the battery 15. The output circuit of the push-pull amplifier includes the anodes 17 and 18 of the tubes 11 and 12, respectively connected to the terminals of the primary winding 20 of the transformer 21. Operating potential for the anode circuit is derived from the voltage source shown here by the battery 22. The output of the amplifier is inductively coupled to the output circuit of the transmission system in that the secondary winding 24 of the transformer 21 is connected by means of conductors 26 and 27 directly to the terminals of the primary winding 28 of the output transformer 29. Both the secondary and primary windings above referred to form a balanced circuit in that the center taps are connected to ground as shown. Effectively in shunt with the conductors 26 and 27 are vacuum tubes 30 and 31, the anode 32 of tube 30 being connected to the conductor 26 and the anode 33 of tube 31 to the conductor 27. The cathodes 34 and 35 of the tubes 30 and 31 respectively, connect to the center tap of the winding 28 and also to ground. The grid circuit of the tubes 30 and 31 includes the interconnected grids 37 and 38 and returns to the grounded cathodes 34 and 35 through the bias source represented here by the battery 40 and the resistor 41 in series therewith. The latter forms the load resistance for the rectifier tubes 42 and 43. The anodes 44 and 45 of the tubes 42 and 43 respectively, connect to the terminals of the secondary winding 46 of the transformer 1 in a conventional full-wave rectifying arrangement in that the center tap connects to ground. The interconnected cathodes 47 and 48 return to ground through the load resistor 41 which is bypassed by the condenser 49.

The transmission circuit just described was chosen as an example to illustrate the application of the control circuit in accordance with this invention. Other types of balanced transmission circuits may as well be used. In certain applications the amplifier stage comprising the tubes 11 and 12 may form any type of time delay network such as high pass, low pass or band-pass filters. In order to simplify the illustration, the heater circuits of the vacuum tubes shown here to be of the indirectly heated types, have been omitted and the operating potential sources are all represented by batteries. It is well known in the art that tubes of this type require a heating current which may be derived from an alternating-current source and that any suitable source of operating potentials may be used. The invention resides in the application of vacuum tubes as variable impedance devices in shunt with a transmission circuit controlled from a potential source which derives energy from currents due to unbalance in the transmission line.

In describing the operation of the system, any unbalance in voltage on the program line feeding the terminals 1 and 2 will produce a current through the primary winding 6 energizing the transformer 7. The voltage induced thereby across the secondary winding 46 is rectified by the tubes 42 and 43 and appears as a charge across the condenser 49. When this voltage reaches a magnitude equal to or greater than the bias voltage of the battery 40, it will effectively neutralize the bias of the grids 37 and 38 and the tubes 30 and 31 will draw plate current. The change of bias initiating current conductivity of the tubes in effect is equivalent to a variable impedance shunting the conductors 26 and 27 to ground and

thereby prevents excessive amplitudes of signal voltages in the transmission circuit. Since the control of the effective anode-cathode resistance of the tubes 30 and 31 depends on the potentials derived from the unbalanced condition, it will be clear that the greater the voltage due to unbalance, proportionately lower will be the effective resistance of the tubes. In other words, an increase of unbalance will inversely decrease the shunting resistance effected by the tubes. At the same time, due to the negative bias provided by the source 40, the control can never lower the transmission circuit voltage beyond the normal predetermined signal level, unless there is an unbalance in the transmission line feeding the circuit. This can be seen with reference to Figs. 2 and 3.

In Fig. 2, the signal voltage appearing across the transmission line terminals 1 and 2 is shown with respect to time as one coordinate, and maximum permissible signal level is indicated between zero and A and B. Curve C shows the variations of signal voltage under normal transmission, the amplitude changes representing a characteristic variation of amplitude due to speech or music. A sudden large peak amplitude exceeding the limits between A and B is shown at point D. This sudden surge may be due to static or other conditions unbalancing the input line. In Fig. 2, the illustration shows the effect of such surge voltages without the control system in accordance with this invention. Fig. 3 shows the signal voltage appearing across conductors 26 and 27 in a magnified form due to the insertion of the amplifier stage in the circuit. The function of the tubes 30 and 31 in suppressing the excessive peak amplitude shows the flattening of the peak away below the maximum permissible signal amplitude values A and B. The dotted lines above that indicate the surge voltage which would appear across the lines 26 and 27 without tubes 30 and 31 in the circuit. The flattening of the peak to nearly zero level occurred when the surge voltage appearing as a direct-current potential across the resistor 41 neutralized the bias from the source 40 to such an extent that the resultant low interval resistance of the anode-cathode path of the tubes 30 and 31 had a shunting effect which decreased the amplitude of the signal voltage. Beyond the predetermined level between A and B, further increase of surge voltage is suppressed by the proportionate decrease of resistance of the tubes 30 and 31 effected by the positive control potential developed across the resistor 41 which increasingly biases the grids 37 and 38 as the surge peak increases merely further lowering the effective shunt resistance.

I claim as my invention:

1. In a circuit, a balanced input line, a transmission channel including an impedance network coupled to said line, an output circuit for said network, a pair of variable impedance elements shunting said network, the effective impedance of said elements being variable upon application of control potentials, means for deriving potentials from current flow due to unbalance in said line, and means for applying said potentials to said variable impedance elements for varying the impedance thereof inversely with the magnitude of said potentials.
2. In a transmission circuit, a balanced input line, a transmission channel including an impedance network coupled to said line, an output circuit for said network, a pair of vacuum tubes each having anode, cathode and control elements

shunting said network, the effective impedance of said elements being variable upon application of potentials to said control elements, means for deriving said potentials from current flow due to unbalance in said line, and means for applying said potentials to said control elements at such polarity as to vary the effective impedance thereof inversely with the magnitude of said potentials.

3. In a transmission circuit, a balanced input line, a transmission channel including an amplifier coupled to said line, an output circuit for said amplifier, a pair of variable impedance elements shunting said output circuit, the effective impedance of said elements being variable upon application of control potentials, means for deriving said potentials from current flow due to unbalance in said line, and means for applying said potentials to said variable impedance elements for varying the impedance thereof inversely with the magnitude of said potentials.

4. In a transmission circuit, a balanced input line, a transmission channel including an impedance network coupled to said line, an output circuit for said network, a pair of vacuum tubes each having anode, cathode and control elements shunting said network, the effective impedance

of said elements being variable upon application of bias potentials to said control elements, means including a circuit common to said balanced input line and a rectifier in said circuit for deriving a bias potential from current flow due to unbalance in said line, and means for applying said potential to said control elements at a polarity causing variation of the impedance thereof inversely with the magnitude of said potential.

5. In a transmission circuit, a balanced input line, a transmission channel including an amplifier, an output circuit for said amplifier, a pair of vacuum tubes having anode, cathode and control elements shunting said output circuits, the shunting impedance of said vacuum tubes being variable upon application of bias potential to said control elements, a fixed source of bias potential maintaining the shunting impedance of said tubes at a value ineffective at normal signal transmission, means for deriving a bias potential from current flow due to unbalance in said line and means for applying said derived bias potential in series with and in opposition to said fixed source for varying the shunting impedance of said tubes inversely with the magnitude of said derived potential.

JOHN R. BOYKIN.
